Primary Examiner — Elizabeth A. Albert(74) Attorney, Agent, or Firm — Eversheds Sutherland
(US) LLP(57) **CLAIM**

We claim the ornamental design for a writing instrument, as shown and described.

DESCRIPTION

FIG. 1 is an upper perspective view showing our new design for a writing instrument.

FIG. 2 is a first side view showing the design of FIG. 1.

FIG. 3 is a second side view showing the design of FIG. 1.

FIG. 4 is a third side view showing the design of FIG. 1.

FIG. 5 is a fourth side view showing the design of FIG. 1.

FIG. 6 is a top view showing the design of FIG. 1.

FIG. 7 is a bottom view showing the design of FIG. 1.

FIG. 8 is another side view showing the design of FIG. 1; and,

FIG. 9 is still another side view showing the design of FIG. 1.

The broken lines in the drawings of FIGS. 1-6, 8 and 9 are included for the purpose of showing portions of the writing instrument that form no part of the claimed design.

1 Claim, 5 Drawing Sheets(56)
